UNITED STATES PATENT OFFICE.

ARTHUR C. TWIGG, OF BIRMINGHAM, ENGLAND.

HOLDER FOR SHAPING, SLOTTING, AND SIMILAR TOOLS.

1,355,930.

Specification of Letters Patent. Patented Oct. 19, 1920.

Application filed February 26, 1920. Serial No. 361,480.

To all whom it may concern:

Be it known that I, ARTHUR CHARLES Twigg, subject of the King of Great Britain, and resident of Birmingham, England, 5 have invented certain new and useful Improvements in Holders for Shaping, Slotting, and Similar Tools, of which the following is a specification.

This invention has reference to holders 10 for shaping, slotting and similar tools, and consists in an improved tool-holder which is particularly adapted for attachment to the head of a hand operated screw press, such as shown and described in British Patent 15 No. 122,981, granted to me May 25, 1918, so as to enable such tool-making and die-cutting operations as internal and external slotting and shaping to be performed with a press-actuated tool instead of by the more 20 usual method of hand-chipping with a hammer. The holder is, however, adapted for use in connection with any shaping, slotting or similar machine in which the head or slide has a reciprocating action.

25 The improved holder embodies a tool housing which is capable of a compound movement relative to the part that is fixed to the reciprocating head or slide of the press or other actuating machine, and is influenced by two sets of springs in a manner 30 which provides an effective double-relief action, whereby, during the return stroke of the machine, the cutting end of the tool is held in spring or yielding contact with the 35 face of the work, thus reducing drag or friction on the tool, preserving the cutting edge, and preventing tool breakages such as are likely to occur where the tool is rigidly held in relation to the reciprocating part. Further, at the commencement of each cutting 40 stroke (during which a positive drive is imparted to the tool) the tool is automatically but positively locked at the appropriate cutting angle, but is disengaged, also 45 automatically, from the locking device when the positive driving effort is removed on the point or edge of the tool being withdrawn at the commencement of the return stroke, so as to allow the spring relief action to become 50 and remain operative until the tool has cleared the work at the end of the return stroke, whereupon the tool becomes again locked in the cutting position before the next cut is started.

55 Another feature of the improved holder is that it admits of an ample range of angu-

lar adjustment or setting of the tool for altering the clearance or cutting angle to an inclination from the vertical suitable to the nature of the work to be performed, which 60 enables, for instance, the tool to be set in a more upright position when slotting or internal shaping operations have to be performed on narrow or restricted surfaces, or 65 in confined positions.

Figure 1 of the accompanying drawings shows an elevation of a form of the improved tool holder adapted for attachment to the vertically-reciprocating head or slide of a hand press. This view shows the tool 70 locked at the selected angle for making its cutting stroke.

Fig. 2 is an underside plan of Fig. 1.

Fig. 3 is a sectional elevation showing the dispositions of the two sets of controlling 75 springs of the relief action.

Fig. 4 is a vertical section of Fig. 1 upon the dotted line α .

The same letters of reference indicate corresponding parts in the several figures.

As will be seen from these drawings, the tool-holder comprises two main parts, viz., a driver-bracket a which is adapted to be rigidly fixed to the head or slide of a press by a bolt passing through the eye a' in the horizontal part a^2 , and a tool housing b wherein the tool c is carried; this housing being mounted between a pair of rigid side-cheeks a^3 , a^4 , on the front of the bracket so as to be capable of a limited compound 85 movement therein when the relief action is operative. That is to say, the housing is provided with horizontal journals or trunnions b' , which have their bearing in a pair 90 of slides d' , d^2 , that are carried in rectangular slots a^5 , a^6 , in the cheeks of the bracket so that the housing and tool (when the latter is disengaged from its locking device) are angularly displaceable on the journal 95 bearings relatively to the bracket, and are also vertically displaceable with the slides d' , d^2 , to an extent limited by the depth of the slots a^5 , a^6 .

The housing is influenced by two sets of springs e , f . The back spring e is interposed between the bracket and the rear bottom part of the housing and exerts an outward thrust on the latter, at a point below the center of its journal bearings, which tends to keep the rear stop surface e' above the said center against the bracket, while the springs f are located between the bottoms 100 105 110

of the slides d' , d^2 , and the cheeks of the bracket and apply a vertical upward thrust through the slides to the said housing which tends to maintain the slides against the 5 upper ends of the slots a^5 , a^6 , during the cutting stroke.

The tool c which is capable of a vertical adjustment in the housing and is locked by suitable clamping devices (such as the 10 screws g) has its head extending above the housing; its upper extremity being formed with a tooth or spur c' which, at the commencement of and during each cutting stroke, is automatically engaged with one 15 or other of the notches h that are cut in the under edge of the overhanging driver portion a^7 of the bracket and is thereby positively locked at the proper cutting angle. When so engaged the thrust exerted by the 20 bracket against the head of the tool gives a direct solid drive during the cutting stroke.

A series of these notches h are provided to admit of the inclination of the tool from 25 the vertical being altered (by turning the housing on its journal bearings) for varying the clearance angle or cutting angle of the same according to requirements, or to the nature of the work which the tool has to 30 perform; it being understood that, in this setting operation, after the tool has been adjusted to the desired inclination by pivoting the housing, it is slid upward in the housing so as to take the head-spur of the same 35 into driving engagement with the particular locking notch h that corresponds to the angular setting of the tool, and then the said tool is fixed in the housing by tightening up the clamping screws. Thus, when 40 adjusted to the maximum inclination, the spur-head of the tool is engaged with the innermost notch as shown in Figs. 1 and 3, whereas when adjusted to a more upright or vertical position, as for working in confined 45 areas, the tool head would be engaged with one or other of outward notches. In all such adjustments, the head of the tool is held up and locked in its engagement with the selected notch (except when the relief 50 action is operative) by the upward thrust of the spring f against the housing slides d' , d^2 .

Assuming the tool is set for working at the maximum inclination from the vertical, 55 the positions of the parts prior to the commencement of a cutting stroke are as shown in the drawings, where the tool is positively locked at the said angle by the engagement of the spur head with the innermost 60 notch of the bracket-overhang a^7 . During the cutting stroke, the positive or rigid drive

is transmitted from the driver overhang of the bracket directly onto the head of the tool, but when the cut is completed and the head of the machine commences its return stroke, the resistance set up by the drag on the tool momentarily retards the return of the slides and housing, or brings about a lifting movement of the bracket relative to the housing, which compresses the bottom springs and disengages the head-spur of the tool from its retaining notch. The housing and tool are then free to move about the center of the journal bearing under the control of the back spring e , so that the tool edge is yieldingly held against the face of the work during the whole of the return stroke, with the consequence that dead or excessive drag or friction is avoided, the cutting edge is preserved, and the risk of 80 breakages is reduced to a minimum.

Immediately the edge of the tool clears the work at the end of the return stroke, the resistance which restrains the bottom spring is relieved, and the said springs expand to 85 lift the slides and restore the head-spur of the tool into driving engagement with its notch in the bracket-overhang, thus correctly and positively re-locking the said tool at the correct angle ready for the next cutting stroke.

Having described my invention, what I claim and desire to secure by Letters Patent is:—

1. A double relief-action tool-holder, comprising a bracket fixture for attachment to the reciprocating slide of the actuating machine, a tool housing journaled to slides in the bracket, a relief-action spring acting on the back of the housing below its journal center, and relief-action springs exerting a lifting thrust against the housing slides. 95

2. A double relief-action tool-holder, comprising a bracket fixture for attachment to the reciprocating slide of the actuating machine, a tool-housing journaled to slides in the bracket, a tool carried by said housing and having a head, a relief-action spring acting on the back of the housing below its journal center, relief-action springs exerting a lifting thrust against the housing slides, and a driver-overhang on the bracket 105 formed with notches adapted to be engaged by the head of the tool prior to and during the cutting stroke, and from which the tool-head is automatically disengaged at the commencement of the return stroke, substantially as herein described. 110

Signed at Birmingham, England, this 6th day of February A. D. 1920,

A. C. TWIGG.
